(57) **CLAIM**

We claim the ornamental design for a dumbbell bench, as shown and described.

DESCRIPTION

FIG. 1 is an isometric view of a dumbbell bench embodying the design.

FIG. 2 is a right elevation view of the design shown in FIG. 1.

FIG. 3 is a left elevation view of the design shown in FIG. 1.

FIG. 4 is a rear elevation view of the design shown in FIG. 1; and,

FIG. 5 is a front elevation view of the design shown in FIG. 1.

The broken lines in the drawings illustrate portions of the dumbbell bench that form no part of the claimed design.

1 Claim, 4 Drawing Sheets
